A. N. SHOOK

HAND LOOM

Filed April 11, 1923

UNITED STATES PATENT OFFICE.

ANNA NOTT SHOOK, OF NEW YORK, N. Y.

HAND LOOM.

Application filed April 11, 1923. Serial No. 631,248.

To all whom it may concern:

Be it known that I, ANNA NOTT SHOOK, a citizen of the United States, residing at New York city, borough of Manhattan, in 5 the county of New York and State of New York, have invented certain new and useful Improvements in Hand Looms, of which the following is a specification.

This invention relates to looms for the 10 weaving of scarfs, table runners, or other fabric compositions, and has particular reference to that type of looms known as hand looms as distinguished from large power operated machines.

15 Among the objects of this invention is to provide a hand loom of such a simple and relatively compact construction as to make it particularly attractive and well adapted for use by ex-soldiers or other convalescents

20 in hospitals or other such institutions, as well as for general domestic use. The construction is adapted for use on the lap or in bed, as well as upon a table wherever the operator may be seated or otherwise sta-

25 tioned, while the relatively movable parts of the mechanism may be easily adjusted for operation in connection with the base or disconnected therefrom for nesting or storage within or upon the base so as to occupy an

30 exceedingly small amount of space for storage or transportation purposes. The entire construction when collapsed or nested is so relatively light and small as to make it well adapted for transportation through the

35 mails, but when in use has a capacity for the weaving of fabrics up to fifteen inches or more in width.

Another object of the invention is to provide a loom that is practically independent

40 of springs or other power mechanism, thus lessening the first cost of the output and tending toward the greatest simplicity and ease of operation in practice, and hence it is practically noiseless, a feature of great 45 importance in connection with hospital practice especially.

A further object of the invention is to provide a heddle so constructed as to be self supported in elevated position in connection

50 with the frame mechanism and to act to hold the shed in its changed position simply by the weight of the heddle.

With the foregoing and other objects in view the invention consists in the arrangement and combination of parts hereinafter described and claimed, and while the inven-

toin is not restricted to the exact details of construction disclosed or suggested herein, still for the purpose of illustrating a practical embodiment thereof reference is had 60 to the accompanying drawings, in which like reference characters designate the same parts in the several views, and in which—

Figure 1 is a perspective view of a preferred embodiment of the invention. 65

Fig. 2 is a vertical longitudinal section of the same.

Fig. 3 is a detail view corresponding to a portion of Fig. 2 but showing the heddle in changed position. 70

Fig. 4 is a detail view indicating particularly the relation of the beater to the warp support.

Referring now more specifically to the drawings I show my improved loom as comprising a base 10 of relatively flat rectangular form including two parallel side pieces 11 and 12. The bottom 13 of the base may be of any suitable construction, but is indicated as being of a solid or closed nature 80 and to the side edges of which the side pieces 11 and 12 are attached. The front and rear of the base are preferably open. 14 indicates a breast beam connected to and extending between the front upper corners of 85 the side pieces, and at the rear corners is a similarly arranged lease bar 15, both serving their usual purposes. The side pieces are provided adjacent to their front and rear ends and on their inner sides with pairs 90 of axially aligned bearing pockets 16, shown as formed in correspondingly arranged plates 17 on the inner side of the base. Each of the pockets opens horizontally toward the 95 opposite end of the base.

The cloth beam 18 is a roller whose ends are journaled in the front pair of pockets 16, the beam being admitted into its bearing pockets from the interior of the base and is locked in such position by keepers in the form of pins 19 spanning the mouths of the pockets. The ends of the beam 18 are provided with metal caps 20 having a series of holes 21 formed radially therein, the holes in one cap being offset or staggered with 105 respect to those in the other cap. Co-operating with these holes and also with the breast beam in alternation are a pair of pins 22 which serve as levers for rotating the cloth beam step by step and in co-action 110 with the breast beam serve to hold the cloth beam in adjusted position. The operator

seated or stationed in front of the loom will draw forward or downward on the uppermost pin 22, causing the rotation of the cloth beam far enough for the other pin 5 to be engaged in the next upper hole at its end. Thus after successive step by step rotations of the cloth beam the proper adjustment thereof and the work attached thereto will be effected and either pin will be sufficient to maintain such adjustment. The warp threads 23 may be attached to the cloth beam in any well known manner.

At the rear end of the base is the warp beam 24 journaled in the rear pockets 16 15 and held in position by pins 19, as above described. The adjustment of the warp beam is effected or controlled by pins 25 co-operating with the whip roll 15. The pins 19 obviously may be put into or removed from 20 operative position by a simple manipulation, and the beams 18 and 24 may be removed or put into place readily as will be obvious, whether warp and work are connected thereto or not.

25 For the best results and most convenient operation the shed portion of the warp should be disposed in an inclined position upon the breast beam so that the person seated in front of the loom will have direct 30 perpendicular vision of the work by looking in the natural direction forward and downward. This fact is of particular importance when the work is of an artistic nature as is so frequently the fact. The warp support 35 comprises a bar 26 constituting the upper portion of the frame whose side members or legs 27 are connected detachably to the front portion of the base, as in keepers 28 extending inward from the side pieces 40 45 11 and 12. These keepers are so positioned that the legs 27 project upward and rearward. Co-operating with the legs 27 are a 50 pair of braces 29 shown as pivoted at 30 to the legs. These braces 29 are provided 45 with inside grooves 31 adjacent to their upper ends. The lower ends of the braces are pointed at 32 and detachably fitted into holes 33 formed in the bottom of the base and whereby the braces are held from lateral 55 movement when in practice. Thus the warp support is rigid in its upright position, but when the warp is loosened, the warp support may be lifted directly out of its connections with the base and folded flat, the 60 parts swinging around the pivots 30. With the warp and work properly rolled upon the cloth and warp beams, the work will of course be kept in proper order and may be received in this condition within the base

65 when not in use.

The heddle comprises a frame 34 with suitable strings 34' co-operating with alternate warp threads in the usual manner. The heddle frame operates in the guide way 65 formed by the grooves or channels 31 in the

70 braces 29. The grooves 31 are enough wider than the thickness of the heddle frame to permit tilting of the heddle with respect to the plane of the braces. When the heddle is down its weight serves to hold it toward 75 or against certain stops 35 carried by the braces, and this position of the heddle determines one of the sheds. For changing the shed the operator simply lifts the heddle as shown in Fig. 2 and when so lifted it will be held by suitable catch means such as a shoulder 36 formed by notching the front portion 80 of the frame, the shoulder engaging over the upper end of the brace 29. I prefer also to notch out the rear portion of each 85 brace forming a shoulder 37 with which each lower corner of the heddle frame co-operates as in Fig. 2. Either form of catch means would suffice but I prefer in practice making both sets of notches. After the weft 90 38 is manipulated as desired, to change the shed again the operator simply touches the top of the heddle tilting it upward and rearward, causing the release thereof so that it will drop by gravity as above explained to 95 the position of Fig. 3.

In the practice of this loom for many purposes no beater is necessary or desirable, especially when the weft is carried by a shuttle which may be employed as a beater. I 100 show, however, at 39 a beater having in general the usual characteristics of comb-like beaters, but having a peculiar relation with the other parts above described. The beater frame comprises two side legs 40 whose lower ends form lugs 41 which co-operate movably or pivotally in holes 42 formed in the base bottom 13. For convenience of construction and assemblage the legs 40 are connected by a cross bar 43 above which the legs 105 are formed with grooves 44 into which the beater proper is fitted at its ends. As shown by full and dotted lines in Fig. 2 the beater is tilttable forward and rearward around the lugs 41 as pivots for its usual purposes. To 110 hold the beater in its upright or rear position temporarily while the weft is being manipulated I provide on the outer sides of the legs 40 a pair of friction members 45 preferably in the nature of vulcanized rubber 115 buttons so designed as to grip frictionally against the inner sides of the weft support legs 27. In other words, the operator simply lifting or moving the beater rearward will bring it naturally and directly into its 120 holding position, and for use of the beater the operator will simply draw forward on the same with a proper degree of force and then return it to its upright position. The 125 movements in the operation of the loom are all easy and natural. There are no springs or other similar parts that are likely to break or get out of order. This structure is easily disconnected and folded or nested within the base, and when so nested may be 130

easily wrapped or put into a shipping case for shipping, carrying, or storage. When nested the structure may be only a few inches in thickness or height and a foot or

5 two square.

I claim:

1. In a loom, the combination with a base including a breast beam and a lease bar, of a warp support extending upward above 10 said base in position to hold the shed at an inclination above the breast beam, means including rotatable beams adapted to be locked against rotation to control the forward adjustment of the warp, and a heddle 15 between the support and the breast beam, said warp support comprising a frame with spaced parallel legs connected to the base and comprising also a pair of brace legs pivoted to the first mentioned legs, the lower 20 ends of the brace legs being detachably connected to the bottom of the base.

2. In a loom, the combination of a base, a warp support supported upon the base, means at the front and rear portions of the 25 base to control the movement and adjustment of the warp over the support, the warp support comprising a pair of brace legs, and a heddle slidable up and down along said brace legs.

30 3. A device as set forth in claim 2 in which the brace legs are provided with

grooves along which the heddle is slidable and relatively tiltable, means being provided to hold the heddle elevated as a result of its tilting movement.

35

4. In a hand loom, the combination with a base, a warp support extending upward from the base and including a pair of spaced legs, and means including rotatable beams co-operating with the base adapted to be 40 locked against rotation to control the forward adjustment of the warp, of beater mechanism movably related to the base and comprising means co-operating with said warp support for holding the beater mechanism in elevated position, said mechanism including a pair of legs having friction buttons so positioned as to co-operate with the adjacent sides of the warp support legs for holding the beater elevated.

45

50 5. In a hand loom, the combination with a base and a warp support extending upward from the base and including spaced leg means, of beater mechanism movably related to the base and having friction buttons so located thereon as to co-operate with said leg means of the warp support for holding temporarily the beater mechanism in predetermined position.

55

In testimony whereof I affix my signature.

ANNA NOTT SHOOK.
